UNITED STATES PATENT OFFICE.

JOHN WRIGHT, OF CLEVELAND, OHIO.

PATTERN-BOARD.

SPECIFICATION forming part of Letters Patent No. 404,144, dated May 28, 1889.

Application filed March 18, 1889. Serial No. 303,797. (No model.)

To all whom it may concern:

Be it known that I, JOHN WRIGHT, a citizen of the United States, residing at Cleveland, in the county of Cuyahoga and State of Ohio, 5 have invented certain new and useful Improvements in Pattern-Boards, of which the following is a specification, reference being had therein to the accompanying drawings.

This invention relates to certain new and 10 useful improvements in pattern-boards.

The object of the invention is to construct a pattern-board in the use of which the process of molding preparatory to casting is materially simplified, particularly in that class 15 of casting embracing stove covers and centers, and it is to that class that this invention more especially appertains.

In the use of the board hereinafter described I am enabled to gate the patterns from a central 20 connecting-gate, doing away with the employment of peripheral or skin gates, which latter leave the castings in such condition as to require grinding before they are ready for market or fit for use.

25 By my process, after the gates have been broken from the castings, such castings are left smooth and clean and require no grinding whatever, and are ready for use after the adhering sand has been removed. I attain the 30 desired object of this present invention by the employment of a pattern-board upon one side of which is secured any desired number of face-plates—four being the number I use for the sake of easy handling—while upon the 35 reverse side of the board or cope side are secured a number of patterns equal to the number of face-plates. These patterns I gate by the use of horn-gates radiating from a central gate, which latter carries an anchor-plate and sprue, the toes of the horns resting upon the 40 sinks of the covers. Each face-plate is also provided with a sliding punch for forming the web across the pit.

The invention consists in the peculiar construction and combinations of the various 45 parts, all as more fully hereinafter described and claimed.

Figure 1 is a perspective view of my improved pattern-board with the gates in place. 50 Fig. 2 is a plan of the face-plate side of the board. Fig. 3 is a similar view of the cope side. Fig. 4 is a vertical section on line $x-x$, Fig. 2.

Fig. 5 is a vertical central section of the gate-patterns.

In the accompanying drawings, which form 55 a part of this specification, A represents a suitable board, in one face or side of which are secured the face-plates B, each of which is provided with a pit, C. Between the face-plate and the board are placed the punches D, which 60 slide in grooves provided for them in the under faces of the face-plates B, and each punch is provided with a stem, E, which projects through a slot, a , in the board, and by means of which said punches may be operated. 65

Upon the cope side of the board are rigidly secured the patterns F, equal in number to the face-plates B. The stems E of the punches D pass through slots b in the patterns, and each stem is provided with a plate, d , for covering the said slot and to prevent sand from 70 clogging the punches.

In the center of the board A, upon the cope side thereof, is formed a depression, A', to receive the gate-plate H, which is provided 75 with the central connecting-gate, H'. In the lower face of the plate H is formed a depression to receive the anchor-plate J, the latter being locked in place by means of a T-headed rod, K, projecting from the small end of the 80 sprue L, said rod K passing through an axial opening in the connecting-gate and gate-plate and engaging with a rectangular slot in the anchor-plate. In the gate-plate is formed a series of openings to receive the heels of the 85 horn-gates, which latter rest upon the anchor-plate, as is clearly shown in the drawings.

I style the plate J an "anchor-plate," for the reason that it, in connection with the T-headed bolt K, secures together in their relative positions the sprue L and central gate, H', while it also forms an anchor for the 90 heels of the horn-gates. The central opening through this anchor-plate is rectangular in form, so that when the head of the bolt is inserted through it and is given a quarter-turn the arms of the bolt-head will engage with the outer face of the said plate and draw it into 95 close contact with the central gate, H', and within the recess designed to receive it.

In practice I first lay the cope down and place the pattern-board thereon with the face-plates up. I then put on the drag and ram up. This being done, the flask is turned over 100

and the gates, anchor-plate, and sprue then put in position, as shown in Fig. 1. I then push out the punches into the cores of the pits already formed, and I then ram up the 5 cope side. The cope is then taken from the drag, the punches withdrawn, and the sprue, gates, and anchor-plate removed. The flask is then closed together and clamped, and it is ready for pouring. After the cast is made 10 the gates are knocked off and the sand removed from the castings in the usual manner, and the covers are ready for shipment or use without the necessity of grinding, as all the contour lines are left perfectly smooth and 15 clean.

Thus it will be seen that I am enabled to dispense with the use of parting-sand, and, having the solid pattern-board to "ram" upon in forming both cope and drag, I obviate all 20 danger of ramming down the one in forming the other, and I am enabled to mold ten flasks an hour as against five flasks under the old method.

In casting stove-lids by the processes now 25 in use, that are provided with core cavities or pits, the so-called "sore" point is at the bottom of such pit, and it is at that point that the castings are disposed to shrink or blow.

By the employment of my herein-described system of gating the patterns these objections 30 are entirely obviated, as will readily be seen and understood by the practical molder, while I am also enabled to pour the flask from one sprue-opening.

What I claim as my invention is—

1. A pattern or match board provided with a series of two or more face-plates and patterns in pairs, substantially as herein described, in combination with horn-gates radiating from a central gate and communicating 40 with a central sprue, substantially in the manner and for the purposes specified.

2. In combination, a pattern-board provided with face-plates and patterns, a series of horn-gates gating to and with a central connecting-gate, an anchor-plate, and a locking-sprue, the parts being constructed, arranged, and operating substantially in the manner and for the purpose described.

In testimony whereof I affix my signature, in 50 presence of two witnesses, this 26th day of December, 1888.

JOHN WRIGHT.
